ATTORNEYS

UNITED STATES PATENT OFFICE.

GEORGE W. STOUT, OF MERCHANTVILLE, NEW JERSEY, ASSIGNOR TO AMERICAN VULCANIZED FIBRE COMPANY, OF WILMINGTON, DELAWARE, A CORPORATION OF DELAWARE.

PACKAGE-TIE.

1,294,321.

Specification of Letters Patent. Patented Feb. 11, 1919.

Application filed June 12, 1917. Serial No. 174,199.

To all whom it may concern:

Be it known that I, GEORGE W. STOUT, a citizen of the United States, residing at Merchantville, in the county of Camden, 5 State of New Jersey, have invented a new and useful Package-Tie, of which the following is a specification.

My invention consists of a novel construction of a package tie having a body portion, which may be constructed of vulcanized fiber, metal, wood or other suitable material possessing the requisite strength and rigidity, said body portion being provided with an extension at one end thereof having 15 inwardly converging outer walls which at their junction with said body are provided with recesses, the opposite end of said body having an inwardly extending oblique slot provided with inwardly converging walls and in a side thereof another inwardly extending shorter oblique slot, and there being an eye between said slots for the reception of the knotted end of the tying cord.

To the above ends my invention consists 25 of a novel construction of a package tie having the distinguishing characteristics hereinafter specifically pointed out in the claims.

For the purpose of illustrating my invention, I have shown in the accompanying 30 drawings one form thereof which is at present preferred by me, since the same will give in practice satisfactory and reliable results, although it is to be understood that the various instrumentalities of which my invention consists can be variously arranged 35 and organized and that my invention is not limited to the precise arrangement and organization of these instrumentalities as herein shown and described.

40 Figure 1 represents a perspective view of a package tie embodying my invention showing also a tying cord and a package or bundle wrapped thereby.

Fig. 2 represents a perspective view of 45 the package tie seen in Fig. 1, in detached position, showing the manner of engaging the tying cord therewith.

Fig. 3 represents a plan view of my novel package tie with the tying cord removed 50 therefrom.

Similar numerals of reference indicate corresponding parts.

Referring to the drawings:

1 designates my novel construction of

package tie, the same comprising a body 55 portion 2, which is preferably of circular or similar contour, and is provided with the tongue or extension 3, having the inwardly converging outer walls 4, which at their point of junction with the body are provided with the recesses 5.

6 designates an inwardly extending oblique slot, cut or kerf having converging walls, whose terminus 7 is preferably extended to or a slight distance beyond the 65 median line of said body drawn through the extension 3. 8 designates a shorter oblique slot, cut or kerf, which is located in proximity to the extension 3 and is provided with the curved terminal seat or recess 9 for the 70 reception of the free end 10 of the tying cord 11, which is inserted through the eccentrically located hole 12 and provided with a knot 13.

The manner of using my invention will 75 be apparent from Figs. 1 and 2, it being apparent that the tying cord 11 after having been wrapped or looped around the package or bundle 12, may be tied by having its free end, drawn within the obliquely extending 80 longer slot 6 and thence passed around one of the recesses 5, its free end being then drawn into the shorter oblique slot, cut or kerf 8, as indicated in Fig. 2, whereupon the package will be securely tied and said free 85 end 10 cannot be disengaged by an accidental pull.

If desired, said free end 10 can be wrapped or looped once or twice around the converging walls 4 of the extension 3, and 90 it will be apparent that other ways of using my device may be employed, if desired.

It will now be apparent that I have devised a novel and useful construction of a 95 package tie, which embodies the features of advantage enumerated as desirable in the statement of the invention and the above description, and while I have in the present instance, shown and described a preferred 100 embodiment thereof which will give in practice satisfactory and reliable results, it is to be understood that the same is susceptible of modification in various particulars without departing from the spirit or scope of 105 the invention or sacrificing any of its advantages.

Having thus described my invention,

what I claim as new and desire to secure by Letters Patent, is:—

1. A package tie, comprising a plate or body, an extension on one end thereof provided with inwardly converging outer walls, an inwardly extending oblique slot located in said body at the end opposite to said extension, and a second shorter oblique slot located in a side of said body at a point nearer said extension, said body having an eye located eccentrically therein out of alignment with said extension and intermediate of said oblique slots.
2. A package tie, comprising a circular body having a diametrical extension at one end thereof, provided with inwardly converging outer walls, said walls merging into

recesses at their point of junction with said body, a slot having inwardly converging walls and its inner terminus located at a point slightly beyond the median line of said body passing through said extension, said body having an eye and a second obliquely extending shorter slot located above said eye provided with inwardly converging walls for the reception of the free end of said tying cord, the longer of said slots having its inner terminus located out of alignment with said extension.

GEORGE W. STOUT.
